UNITED STATES PATENT OFFICE.

ABBOTT L. COMBES AND HARRY M. KEYSER, OF EAST FALLS CHURCH, VIRGINIA.

RIPPING UNIT FOR METAL CANS.

Refiled for abandoned application Serial No. 748,719, filed November 8, 1924. This application filed June 8, 1926. Serial No. 114,576.

This invention relates to an improved can ripping unit of the general character disclosed in our co-pending application for ripping unit for metal cans, filed June 8, 1926, 5 Ser. No. 114,575, and seeks, among other objects, to provide a unit embodying a carrier ring and ripping element, and wherein the unit will be formed as an integral structure.

The invention seeks, as a further object, 10 to provide a unit which may be stamped as a blank from suitable sheet metal and the blank fashioned to produce the unit.

And the invention seeks, as a still further object, to provide a unit which will accomplish the several objects and serve the same useful purpose of the ripping unit disclosed in our co-pending application above identified.

Other objects of the invention not specifically mentioned in the foregoing will appear during the course of the following description. The present application is a substitute for the applicants' abandoned application filed November 8, 1924, Serial No. 25 748,719.

In the accompanying drawings:

Figure 1 is a perspective view showing the improved ripping unit mounted in a conventional can, parts being broken away and 10 illustrated in section.

Figure 2 is a detail perspective view of the unit, broken away and shown in section.

Figure 3 is a plan view of the blank from 5 which the unit is formed.

Figure 4 is a plan view showing the manner in which one margin of the blank is rolled to form a ripping element thereon.

Figure 5 is an enlarged detail cross sectional perspective view particularly showing the formation of the ripping element.

Figure 6 is an enlarged cross sectional perspective view showing a slight modification of the invention.

Figure 7 is a fragmentary perspective view showing a further slight modification of the invention.

In accordance with the present invention, an oblong blank 10, as shown in Figure 3 10 of the drawings, is struck from suitable sheet metal. At one end, the blank is stepped and formed in the blank in alignment with the upper edge of the stepped portion thereof is a line of closely spaced slits 11 terminating short of the opposite end of the blank,

The lower margin of the blank is tightly rolled upon itself, in the manner best shown in Figure 5, to provide a ripping element 12 cylindrical in cross section, when the blank is, as shown in Figure 4, bent into annular 60 shape so that the upper margin of the blank provides a carrier ring 13 for said element. Thus, an integral ripping unit embodying a carrier ring and ripping element at the inner side of the ring is produced. Preferably, 65 the ripping element lies substantially flush with the line of slits 11 so that said slits thus serve to weaken the connection between the carrier ring and said element and, as will be observed, the ripping element is longer 70 than the ring, thus permitting the free end 14 of said element to be bent up at one end of the ring. The ends of the ring may or may not be joined, as found most desirable.

In Figure 1 of the drawings, we have 75 shown the device installed in a conventional can 15. The lid of the can is indicated at 16 and, in accordance with prevalent practice, the lid is provided with a peripheral flange 17 which is crimped around a flange 80 18 on the side wall of the can for sealing the can and securing the lid in place. Before the lid is applied, the carrier ring 13 is slipped over the base of the flange 17 of the lid while the terminal 14 of the ripping element is coincidentally inserted through a suitable opening in the lid. Thus, the lid, with the ripping unit thereon, may be pressed into the upper end of the can, when the can is crimped, as previously noted, for permanently mounting the lid. The terminal 14 of the ripping element is then bent inwardly away from the rim of the can, preferably in the manner shown, and equipped with a key 19. We have illustrated a key 90 which is struck from suitable sheet metal and is formed near its outer end with an upstanding loop 20. As will be observed, the terminal 14 is inserted through said loop and bent to form a hook 21 permanently 100 connecting the key with the ripping element to normally lie flat against the lid. Accidental loss of the key is thus obviated while the key will always be readily accessible. Having attached the key, the opening in the lid which accommodates the terminal 14 of the ripping element is finally 105 closed with solder for sealing the can.

Attention is now directed to the fact that the crimping of the lid upon the can serves 110

to also bend the upper margin of the carrier ring 13 outwardly so that the carrier ring is thus formed with an annular lip or flange 22 which engages over the upper edge of the 5 side wall of the can and is clamped downwardly thereagainst by the flange 17 of the lid. The lip 22 will, therefore, be tightly held to support the ripping unit against downward movement into the can while the 10 carrier ring will be tightly clamped between the flange 17 and the side wall of the can. Further, the lid rests against the ripping element 12 so that the ripping unit will be rigidly and securely bound in place. Acting 15 accordingly, by grasping the key 19 and turning the element 12 thereon, said element will be torn from the carrier ring 13 along the line of slits 11 and caused to rip the lid 16 in a circular line close to the side wall of 20 the can. The can may thus be easily and quickly opened.

In Figure 6 of the drawings, we have illustrated a slight modification of the invention embodying a ripping unit wherein the carrier ring 23 and ripping element 24 are integrally shaped. The ripping element, which is preferably cylindrical in cross section like the element 12 of Figures 1 and 2, is, therefore, solid, but it is to be understood that 25 the ripping element will be capable of being readily flexed so that it may be wound upon a key, like the key 19 and caused to rip a can wall. Formed in the ring 23 immediately above the ripping element is a line 30 of slits 25. Otherwise, this modified structure is identical with the preferred embodiment of the invention and further description is accordingly believed unnecessary. However, it is desired to note that while we 35 have illustrated and described an annular ripping unit for use in connection with cylindrical cans, still, we are aware that cans of other shapes are employed for containing food-stuffs. In any such instance, the ripping 40 unit will, of course, be shaped accordingly and the term "carrier ring" as herein used shall, therefore, be construed to cover such 45 variations in shape.

In Figure 7 of the drawings, we have 50 shown a further slight modification of the invention wherein the ripping unit is provided with a ripping element as previously described but said ripping element is not only formed at one end with a free terminal 55 26 but is also formed at its opposite end with a free terminal 27. We have illustrated the modified structure in connection with a conventional can 28 and, as will be observed,

the terminal 26 is arranged to extend through the top wall of the can to receive a 60 key 29 like the key 19 of Figure 1, while the terminal 27 is arranged to extend through the side wall of the can preferably at the seam therein. Thus, should it be desired to rip the side wall of the can instead 65 of the top wall thereof, a key may be applied to the terminal 27 and the key operated to roll the ripping element thereon for ripping said side wall.

Having thus described the invention, what 70 we claim is:

1. An attachment for metal cans comprising a ripping unit including a carrier ring to be enclosed in a can and fashioned with an integral ripping element for ripping a wall 75 of the can, the ring being formed with a line of slits weakening the connection between said element and the ring.

2. An attachment for metal cans comprising a ripping unit formed from a blank having one margin thereof rolled to form a ripping element and the opposite margin of the blank providing a carrier ring for said element.

3. An attachment for metal cans comprising a ripping unit including a carrier ring fashioned with a rolled ripping element.

4. An attachment for metal cans comprising a ripping unit formed from a blank shaped to define a carrier ring having a ripping element thereon formed from the material of the blank.

5. An attachment for metal cans comprising a ripping element formed from a blank shaped to define a carrier ring having a ripping element thereon produced from the material of the blank, the blank being mutilated for weakening the connection between said element and the ring.

6. A blank for ripping units comprising 10 an oblong metallic strip stepped at one end thereof.

7. A blank for ripping units comprising an oblong metallic strip stepped at one end thereof and mutilated longitudinally substantially in alignment with the upper edge of its stepped portion.

8. As a new article of manufacture, a separate ripping unit for metal containers, said unit being shaped from a blank having one 11 margin thereof formed into a bulb providing a ripping element.

In testimony whereof we affix our signatures.

ABBOTT L. COMBES.
HARRY M. KEYSER.
